UNITED STATES PATENT OFFICE.

HARRY SAWYER, OF MUSKEGON, MICHIGAN, ASSIGNOR TO SHAW ELECTRIC CRANE COMPANY, OF MUSKEGON, MICHIGAN, A CORPORATION OF MICHIGAN.

SPEED-CONTROL MECHANISM FOR POWER-DRIVEN APPARATUS.

1,263,125.

Specification of Letters Patent. Patented Apr. 16, 1918.

Application filed August 16, 1916. Serial No. 115,201.

To all whom it may concern:

Be it known that I, HARRY SAWYER, a citizen of the United States, residing at Muskegon, in the county of Muskegon, 5 State of Michigan, have made a certain new and useful Invention in Speed - Control Mechanism for Power - Driven Apparatus, of which the following is a specification.

This invention relates to speed control 10 mechanism for power driven apparatus.

The object of the invention is to provide mechanism which is simple and efficient for varying or controlling the speed at which hoisting or other power driven apparatus 15 may be operated.

Other objects of the invention will appear more fully hereinafter.

The invention consists substantially in the construction, combination, location and relative arrangement of parts, all as will be more fully hereinafter set forth, as shown 20 in the accompanying drawings, and finally pointed out in the appended claims.

Referring to the drawings:—

25 Fig. 1 is a view in top plan, parts broken out and parts in horizontal section, showing a speed control mechanism as applied to power driven hoisting apparatus.

Fig. 2 is a broken view in top plan, on a 30 somewhat larger scale than Fig. 1, parts in horizontal section, showing a speed control gearing structure embodying the principles of my invention.

Fig. 3 is a view in vertical transverse section on the line 3, 3, Fig. 2, looking in the direction of the arrows.

The same part is designated by the same reference, numeral wherever it occurs throughout the several views.

40 In the operation of various kinds of power driven apparatus it is sometimes desirable to secure a wide range of variation of the speed at which such apparatus is driven. It is among the special purposes 45 of my present invention to provide a structure which is simple, direct in action, and efficient for securing this result.

In accordance with my invention I propose to employ independent motors for actuating the apparatus to be driven and a gearing common to both motors and adapted to be operated by each, independently of the other, or conjointly by both, for transmit-

ting the driving power to the apparatus to be driven, and through the independent or 55 conjoint operation of which motors the desired speed variations are secured, and through which a wider range of variations is attained than is possible from a single motor.

60 While a speed varying mechanism embodying my invention is adapted for use generally in connection with motor driven apparatus, and for various uses and purposes, I will describe the same as applied 65 to the operation of hoisting apparatus, as one form of practical use thereof.

In the drawings 4 designates a hoisting drum, which, in this instance, is the part which is to be power driven, and 5 is the 70 main power shaft from which the drum is driven through any desired intermediate gear connections, comprising in the example shown, the gears 6, 7. These, however, are mere details and form no part of 75 my present invention.

Power is applied from the motors 8, 9, either independently of or conjointly with each other, to the shaft 5. In the particular form shown, to which, however, my invention is not to be limited or restricted, the motor 8 may be regarded, in this instance, as the main hoist motor. This motor is suitably connected to drive a spur gear 10 which is encompassed by an internally toothed 80 annular gear 11, which is driven from the motor 9. A carrier 12 is connected to rotate with the shaft 5 and upon said carrier are mounted pinions 13, capable of axial rotation upon pins 14^a carried by the carrier 12. The pinions 13 are disposed between and mesh with the spur gear 10 and the internally toothed annular gear 11. In the particular form shown, to which, however, my invention is not to be limited or 90 restricted, three pinions 13 are employed and they are circumferentially spaced at equal distances apart. This gear arrangement constitutes a planetary gear system through which the shaft 5, and hence, the 95 drum 4 is driven whether the one or the other or both motors are in operation. Any suitable form of gearing may be employed between the motor 9 and gear 11 to drive the latter. In the form shown, to which, how- 100 ever, my invention is not to be limited or

105

restricted, I employ a worm gear connection 14 for this purpose, one member of which is connected to the shaft of motor 9, and the other to the wheel 15, which 5 carries the annular internally toothed gear 11. The advantage of this arrangement is that where a worm gear is employed it is enabled to employ the friction of the worm gear or of its end thrust bearing, or the two 10 combined, as a means to hold the worm gear from rotating while the spur gear 10 is being independently driven by the hoisting motor 8 without the operation of the speed control motor 9. In other words, 15 where it is desired to arrest the motor 9 and affect the speed operation solely from motor 8, then the friction of the worm gear and of its end thrust bearing is utilized to restrain the worm gear from rotation.

20 The operation is exceedingly simple. Suppose the motor 8 is in operation with the motor 9 standing still. In this case the spur gear 10 will be rotated while the internal gear 11 will be fixed. By reason of the 25 meshing of the pinions 13 with the rotating spur gear 10 and also with the fixed internal gear 11, said pinions are not only rotated axially but they also travel around within the internal gear 11, thereby imparting rotation to their carrier 12, and hence to the shaft 5, and apparatus to be driven, and at a speed and in a direction dependent upon the speed and direction of motor 8, and the gear ratios employed. On the other 30 hand, if motor 8 is standing still and motor 9 is put into operation, then the spur gear 11 is rotated, thereby causing the pinions 13 to travel around the spur gear 10, and to rotate their carrier and the shaft 5 and hence 35 the apparatus to be driven, at a speed and in a direction dependent upon the speed and direction of the motor 9, and the gear ratios employed. By using a worm gear connection between the motor 9 and internal gear 40 11, a very slow speed of operation of the apparatus to be driven may be attained. Hence, if desired, the motor 8 may be regarded as the speed motor and the motor 9 as the slow speed motor. By operating both 45 motors 8 and 9 in unison in either direction a speed of operation of the apparatus to be driven is attained which equals the sum of the speeds of the motors if operated separately, and hence at a greater speed than 50 is attained with either motor acting singly. By operating the two motors coincidentally but in relatively opposite directions a speed of operation of the apparatus to be driven is attained which equals the difference be- 55 tween the speeds which would be attained by the motors operating separately, thus attaining a wide variation in the speed of operation.

It will be observed that the wheel 15 is 60 not mounted directly on the shaft of pinion

10, but is mounted upon a sleeve 16, which is suitably mounted in fixed position in the casting 17, and the shaft of spur gear 10 extends longitudinally through said sleeve. This construction relieves the spur gear shaft of 70 any wear or friction due to side thrust imposed by the planetary gear system, and consequent loss of power, imperfect action, looseness of parts, and noisy operation of the planetary gears.

75

From the foregoing description it will be seen that fundamentally the essential characteristic of my invention is the application of a gear system which can be driven by either one or two motors or other sources of 80 power, either one of which may be in operation and the other standing still, or both of them operating at the same time, if desired, and either in the same or in relatively opposite directions, thereby securing the desired 85 range of speed variation, according to the character of work to be performed.

Variations and changes in the details may readily occur to persons skilled in the art and still fall within the spirit and scope of 90 my invention. I do not desire, therefore, to be limited or restricted to the exact details shown and described.

But having now set forth the objects and nature of my invention, and a construction 95 embodying the principles thereof, what I claim as new and useful and of my own invention, and desire to secure by Letters Patent is:—

1. In a speed control mechanism, the combination with a part to be driven, and a drive shaft therefor, of a carrier-mounted on said shaft at one end thereof, pinions mounted on said carrier, a spur gear and an internally toothed gear, between which said 100 pinions are positioned and with which they are meshed, a shaft arranged in line with the drive shaft and carrying said spur gear at the end thereof proximate to said carrier, a motor for driving said shaft, said internally toothed gear being journaled independently of said shaft, and an independent motor for driving said internally toothed gear.

105

2. In a speed control mechanism, the combination with a part to be driven, of a carrier connected thereto, pinions mounted thereon, a spur gear and an internally toothed gear, between which said pinions are positioned and with which they are meshed, a motor for driving said spur gear, a 115 fixed bearing sleeve, said internally toothed gear being journaled to rotate on said sleeve, and an independent motor for driving said internally toothed gear.

115

3. In a speed control mechanism, a part to be driven, a driving shaft therefor, a carrier mounted on said shaft to rotate therewith, pinions supported by said carrier, a spur gear, an independent shaft therefor, a 125 motor for driving the spur gear shaft, an 130

120

125

internally toothed gear encompassing said spur gear, said pinions being interposed between and meshing with said spur gear and internally toothed gear, a worm gear connected to said internally toothed gear, and an independent motor for driving said worm gear.

In testimony whereof I have hereunto set

my hand in the presence of the subscribing witnesses, on this 18th day of July A. D., 1916.

HARRY SAWYER.
